UNITED STATES PATENT OFFICE.

GEORGE R. MOON, OF CLEVELAND, OHIO.

OVEN.

No. 823,288.

Specification of Letters Patent.

Patented June 12, 1906.

Application filed October 20, 1905. Serial No. 283,591.

To all whom it may concern:

Be it known that I, GEORGE R. MOON, a citizen of the United States, residing at Cleveland, in the county of Cuyahoga and State of Ohio, have invented certain new and useful Improvements in Ovens, of which the following is a specification.

My invention relates to new and useful improvements in ovens.

10 The object of the invention is to provide within the oven a spreading or deflecting drum into which air is admitted from the exterior of the casing. This drum serves two purposes—that of supplying air to the 15 burners for properly supporting combustion and preventing overheating of the lower part of the heating-compartment.

Still another feature resides in the arrangement and construction of the parts whereby 20 the distribution of the heat products is equalized and the said products fully deprived of their heat before escaping from the oven.

Finally, the object of the invention is to provide a device of the character described 25 that will be strong, durable, and efficient and simple and comparatively inexpensive to produce.

With the above and other objects in view the invention consists of the novel details of 30 construction and operation, a preferable embodiment of which is described in the specification and illustrated in the accompanying drawings, wherein—

Figure 1 is a longitudinal vertical sectional view taken on the line $z z$ of Fig. 2. Fig. 2 is 35 a transverse vertical sectional view taken on the line $y y$ of Fig. 1. Fig. 3 is a horizontal cross-sectional view taken on the line $a a$ of Fig. 1, and Fig. 4 is a transverse vertical sectional view taken on the line $b b$ of Fig. 1.

In the drawings, the numeral 1 designates the casing of the oven, which is substantially 40 rectangular in cross-section and constructed of any suitable sheet metal. At the central portion of its top an outlet or escape opening 2 is provided. Some distance above the bottom of the oven an air-drum 3, triangular in cross-section, is arranged, extending longitudinally of the oven between the end walls. 45 The drum is securely fixed in place and at each end is provided with air-inlet openings 4, which communicate and register with air-openings 5, formed in the end walls. The apex of the drum, which is directed down- 50 ward, is provided with a plurality of openings 6, through which the air admitted by the

openings 4 and 5 is ejected. Slightly below the drum and on each side of the apex thereof parallel gas-burners 7 are provided. By provision of the air-drum 3 a sufficient quantity of air is supplied to the burners to properly support combustion, while at the same time the upwardly-inclined sides of the drum act to spread or deflect the heat products from the burners, so as to cause an equal distribution of the same, as will be hereinafter described. The upper side of the drum 3, which is flat, supports and forms the bottom of a heating-compartment A, at the front of which the oven is provided with an opening 8, 60 covered by a suitable door or closure 9. The sides of the compartment A are formed by vertical side or end plates 10, which extend entirely from the front to the back of the oven and are covered by a top plate 11, extending 65 in a like manner. The back of the compartment is formed by a vertical plate or wall 12, which extends upwardly from the drum 3, but terminates short of the under side of the top plate 11, so as to provide an inlet-opening 13. The compartment A is divided into two cells by means of a shelf or horizontal plate 14, which terminates short of the front wall of the oven, so as to provide communication between the two cells. Outlet-openings 80 15 and 16 are provided in the end walls 10 of the compartment, the openings 15 being positioned near the forward end of the upper cell and the openings 16 arranged near the rear end of the lower cell. These openings 90 provide for the escape of the products from the cells after the same have passed therethrough. The end or side walls 10 provide with the end or side walls of the oven-casing vertical flues B, which terminate at their upper end in a horizontal flue or chamber C, 95 formed by the top plate 11 and the top of the oven-casing, while the wall or plate 12 of the compartment A forms with the rear or back wall of the oven-casing a vertical heat-conducting flue D, said flue being closed at its upper end by the plate 11, but having communication through the opening 13 with the upper cell of the compartment.

Referring to Fig. 2, it will be obvious that 105 the heat products generated by the right-hand burner 7 will be directed by the drum 3 into the vertical heat-conducting flue D, up which they will pass through the opening 13 into the upper cell of the compartment A, 110 while the heat products generated by the burner 7 on the left-hand side of the drum

will be deflected and directed by the same so as to pass up into the lower cell of the compartment A, circulating therein and fully heating the same. The heat products passing to the rear of the lower cell will escape through the opening 16 into the side flues B, (see Figs. 1 and 2,) while the products at the forward end of the said lower cell will pass up around the front edge of the shelf 14 into the upper cell, where they will circulate and mingle with the products entering through the opening 13, all the products finally passing out through the openings 15 into the vertical flues B, where mixing with the products from the openings 16 they will pass upward into the horizontal flue C and finally escape through the opening 2.

It will be apparent that by delivering a greater amount of heat to the upper cell of the compartment and by provision of the cold-air drum 3 at the bottom of the lower cell the compartments are equally heated and the heat so regulated that one cell receives comparatively the same amount as the other.

Having now fully described my invention, what I claim, and desire to secure by Letters Patent, is—

1. An oven comprising an outer casing, a drum extending from end to end of said casing and having outlet-openings at the bottom thereof, gas-burners arranged upon each side of said outlet-openings, and a baking-chamber located above said drum, the interior of said drum being in communication with the atmosphere.

2. An oven comprising an outer casing, a drum extending from end to end of said casing, said drum being triangular in cross-section and forming inclined side walls, the interior of said drum being in communication with the atmosphere and with the interior of the outer casing through openings formed at the lower

portion of said drum, gas-burners arranged adjacent said drum upon each side of said openings, and a baking-chamber located above said drum. 45

3. An oven comprising an outer casing, a drum extending lengthwise of said casing, the interior of said drum being in communication with the atmosphere and said drum having air-outlet openings at its bottom, gas-burners arranged adjacent said outlet-openings, a baking-chamber located above said drum, means for conducting the heat from one of said gas-burners to the upper portion of the baking-chamber, means for conducting the heat from the other of said gas-burners to the lower portion of the baking-chamber, and means for permitting the passage of heat from the upper and lower portions of the baking-chamber to the interior of the outer casing. 55 60

4. An oven comprising an outer casing, partitions located in said outer casing and forming a baking-chamber, said partitions comprising two side walls, a top wall and a rear wall which terminates short of the top wall, a deflecting-drum which forms the bottom of the oven, the interior of said drum being in communication with the atmosphere 70 and said drum having air-outlet openings in its lower portion, burners arranged upon each side of said outlet-openings and said deflecting-drum being adapted to direct the products of combustion from one of said burners 75 to a passage formed between the rear wall of the baking-chamber and the outer casing and to direct the products of combustion from the other of said burners to the lower portion of the baking-chamber. 80

In testimony whereof I affix my signature in presence of two witnesses.
